UNITED STATES PATENT OFFICE.

CHARLES P. BAKER, OF PAINESVILLE, OHIO.

VEGETABLE-TOPPING MACHINE.

1,110,370.

Specification of Letters Patent. Patented Sept. 15, 1914.

Application filed May 25, 1911. Serial No. 629,317.

To all whom it may concern:

Be it known that I, CHARLES P. BAKER, a citizen of the United States of America, residing at Painesville, in the county of 5 Lake and State of Ohio, have invented certain new and useful Improvements in Vegetable-Topping Machines, of which the following is a specification.

My invention relates to improvements in 10 vegetable topping machinery, and has for its object the provision of mechanism which is cheap in construction, and adapted to remove the tops from vegetables, such as onions, beets, and the like.

15 Prior machines of this general character have required the provision of two or more cooperating rollers, optionally provided with cutting edges, or a spiral-bladed rotary member associated with a stationary metallic cutting edge. I have discovered, however, that somewhat analogous but more efficient mechanism may be constructed by employing a straight-bladed rotary member, in association with a non-rotatable, 20 semi-resilient member against which the tops may be expeditiously broken or scraped from the bulb of the vegetable. This discovery is based upon the fact that onion tops are most expeditiously severed by 25 striking them a sharp rapid blow when resting against a substantially stationary wooden surface. Moreover, the vegetable tops may be readily drawn into position for operating thereon, by means of a strong current of 30 air. The bladed member in my machine, accordingly, is provided with means for very rapidly rotating the same, in order to secure a suction effect by means of the relatively wide blades or fans, thereby drawing 35 the tops of the vegetables into position for severing the same. I may also provide 40 separate means for agitating or rocking the receptacle for the vegetables, to assist in the topping operation.

45 Further details of my improved construction may be more readily explained in connection with the accompanying drawings wherein

Figure 1 is a view in end elevation of my 50 improved vegetable topping machine; Fig. 2 is an enlarged detail of the lower end, and Fig. 3 a similarly enlarged detail of

the upper end of said machine; Fig. 4 is a transverse sectional view of the rotary bladed member; Fig. 5 is an end view of a 55 slightly modified form of my improved vegetable topping machine; Fig. 6 is an enlarged detail of a modification thereof affording double capacity for topping; Fig. 7 is an end view illustrating principally the 60 driving mechanism of the machine shown in Fig. 5, and Fig. 8 is a detail of the machine of Fig. 6.

Throughout the several figures of the drawings I have employed the same character of reference to indicate similar parts.

A description of the features of one of these machines will apply largely to each of the others, and I may refer first to Fig. 1, which shows a single vegetable topping machine mounted in inclined position upon the supporting frame *a*. A rotary-bladed member *b*, provided with renewable and relatively wide blades *c*, is mounted in journal bearings *b'* at either end of the frame. This rotary 70 member is adapted to be rapidly driven by means of the gears *d'* and *d''* and may well be propelled by hand or any suitable power connection. A tilting cover or casing *e* is superposed above the rotary-bladed member, 75 while a semi-resilient member, such as wooden block *f*, having a beveled face, is positioned opposite the bladed member *b* against which the straight blades are adapted to strike or rub along its lower edge for 80 about three-quarters of an inch. A flat spring *g* and coil springs *h* within end housings *h'*, yieldingly hold the member *f* in position, which may be adjusted by means of the set-screws *i*, *i'*. Baffle strips *f'* may be 85 provided upon the inclined face of member *f*, and a hopper *j* suitably supported upon the frame, may be advantageously positioned at one side of the machine for supplying vegetables to be topped.

95 The general construction of the machine in Fig. 5 will now be quite apparent, but, in addition, I have provided a sheet-metal member *k* attached to the wooden strip *f*, which is adapted to be constantly rocked 100 by means of the eccentric *k'* and its connecting rod *k''*. By reason of the constant and rapid impact of the straight blades *c* against the member *f''* during the rapid ro-

tation of the former, there will necessarily be considerable vibration, but by the provision of the means above shown the vegetables will be more effectually agitated and thus cause them to present their tops for severing the same from the bulbs.

In the double-acting machine shown in Fig. 6, with the detail in Fig. 8, the curved lateral members *k* *k*' are provided upon either side and a wooden strip *l* is associated with the semi-cylindrical casing or cover *m*, so that the blades *c*, when rotated in clockwise direction, will strike the member *f*' upon the right and the strip *l* upon the left, (member *f*^o being adjusted so that the blades will clear it) thereby severing the tops from the vegetables at either side of the machine and practically doubling its capacity. In any or all of these machines, especially when hand power is used, I may employ ball bearings mounted in casing *n* at either end of the rotary-bladed member, for permitting the same to be more easily driven and taking up the end-thrust of this inclined member.

The operation of these machines may now be briefly referred to. When, through the medium of the train of gears, rapid rotary motion is imparted to the flat-bladed member *b*, the straight and relatively wide blades thereon will act as fans and cause a suction tending to draw the tops of the vegetables through the longitudinal slot in the machine. This action is assisted, as well, by the natural vibration caused by the blades *c* rapidly striking against the members *f* and *l* and as the vegetables roll down the inclined slotted receptacle therefor, the tops will be caught between the blades and the opposing wooden members, and scraped or broken off, after which the vegetables will naturally fall into a basket or other receptacle provided at the end of the machine.

By providing a wooden or other semi-resilient strip against which the blades may strike, not only is the severing of the tops better accomplished, but the cost of manufacture and renewal is much less than if a metallic co-acting part were employed. Again, if the wooden strip is not perfectly straight initially, it will soon be worn into conformity with the blades, by their rapid impact against the same and the adjustment may readily be effected within the end housings by means of the adjustment screws and springs. The strip *l* may also be resiliently held in the manner shown, or in any approved manner and may be renewed when worn.

Having now described preferred embodiments of my improved vegetable topping machine, I claim as new, and desire to secure by Letters Patent, the following:

1. In a vegetable topping machine, the

combination with a rotary member of a plurality of straight wide blades provided thereon, a casing covering the upper portion of the rotary member, means for rapidly rotating said member, a non-rotatable, semi-resilient member against which the blades are adapted successively to strike during their rotation and a spring-mounting yieldingly holding the said parts in position for engagement, substantially as set forth. 65

2. In a vegetable topping machine, the combination with a rotary member, of a plurality of straight wide blades provided thereon to insure a fan-like action, a train of gears for rapidly rotating said member, a casing partially inclosing said member, a non-rotatable, semi-resilient member against which the blades are adapted to strike in succession during their rotation, and resilient adjusting means for the latter, substantially as set forth. 75

3. In a vegetable topping machine, the combination with a rotary member, of a plurality of straight wide blades provided thereon to insure a fan-like action, a train of gears for rapidly rotating said member, a casing partially inclosing said member affording means for supporting the vegetables above the blades, and plurality of non-rotatable, semi-resilient members positioned at opposite sides of the machine and adapted to be successively engaged by each of the blades during their rotation, substantially as set forth. 90

4. In a weight tapping machine, the combination with a rotary member, a plurality of blades thereon, means for driving said member, a casing or cover positioned over said member, an adjustable co-acting part against which the blades are adapted to strike, a sheet-metal receptacle, and means for rocking the receptacle, substantially as set forth. 100

5. In a vegetable topping machine, the combination with a rotary member provided with a plurality of blades of a train of gears for rapidly rotating said member, a casing partially inclosing said member from above and adapted to support the vegetables, and non-rotatable co-acting parts provided on either side thereof, whereby the capacity of the machine may be increased, substantially as set forth. 110

6. In a vegetable topping machine, the combination with a series of straight rotatable blades, of a non-rotatable, semi-resilient member against which the said blades are adapted successively to strike during their rotation, a spring-mounting yieldingly holding the said parts in position for engagement, means for supporting the vegetables adjacent to the blades, and means for rapidly rotating said blades, substantially as set forth. 120

7. In a vegetable topping machine, the combination with a rotary member provided with a plurality of continuous fan-like blades, of a semi-resilient wooden member 5 against the edge of which said blades are adapted to strike during their rotation, an adjustable spring mounting therefor, means co-acting with said wooden-member for supporting the vegetables adjacent to the blades,

and means for rapidly driving said rotary member, substantially as set forth.

In testimony whereof I do now affix my signature in the presence of two witnesses.

CHARLES P. BAKER.

Washington, D. C."

Correction in Letters Patent No. 1,110,370.

It is hereby certified that in Letters Patent No. 1,110,370, granted September 15, 1914, upon the application of Charles P. Baker, of Painesville, Ohio, for an improvement in "Vegetable-Topping Machines," an error appears in the printed specification requiring correction as follows: Page 2, line 99, for the words "weight tapping" read *vegetable topping*; and that the said Letters Patent should be read with this correction therein that the same may conform to the record of the case in the Patent Office.

Signed and sealed this 6th day of October, A. D., 1914.

[SEAL.]

R. F. WHITEHEAD,

Acting Commissioner of Patents.
